SUPERHEATER

Application filed April 2, 1926. Serial No. 99,358.

This invention relates to superheaters particularly adapted for locomotive boilers and is of the type in which superheater tubes are extended into the fire tubes of the locomotive boiler and are connected to headers disposed in front of the tube sheet.

5 Superheaters of this type, as commonly arranged, require a large variety of different types of superheater tubes to be kept in stock to replace superheater tubes in various parts of the same locomotive boiler and, in order to obtain access to some defective tube, it has heretofore been necessary to remove a number of obstructing sound tubes.

10 An object of this arrangement is the provision of a superheater of the type above set forth wherein the superheater tubes are identical in construction, or at least, the tubes for the right hand side of the boiler are identical, and the tubes for the left hand side of the boiler are identical, although the right and left hand tubes may be differently shaped. Consequently but one or two types of tubes 15 need be kept in stock for repair work.

20 It is a further object of this invention to provide a superheater wherein each tube may be removed independently of other tubes so that the labor and time involved in making 25 repairs is minimized.

30 A further object of the invention is the provision of a superheater wherein the number of joints between the superheater tubes and the saturated and superheated steam headers are minimized.

35 A yet further object of the invention is the provision of saturated and superheated steam headers having branches for connection with the superheater tubes extended in front of the boiler sheet, with the branches being free and 40 independent of each other except in so far as they are connected through the superheater tubes, thereby to provide for the free and independent expansion of the saturated and superheated steam branches.

45 A further object is generally to improve the construction of superheaters.

Fig. 1 is a sectional elevation through the front end of a locomotive boiler with the superheater embodying this invention disposed 50 therein.

Fig. 2 is a front elevation of the tube sheet of the locomotive boiler and the superheater headers, the right half of Fig. 2 being a front view of the tube sheet.

Fig. 3 is a plan view of the superheater tubes of one superheater unit, the tubes being spread apart for clearness.

Fig. 4 is a plan illustrating the manner of clamping the joints between adjacent sections of the header branches.

Fig. 5 is a detailed sectional elevation of the detachable joint between two contiguous sections of a header branch.

Fig. 6 is a more or less diagrammatic view, looking down upon the ends of the superheater tubes to illustrate the staggered relation of the superheated and saturated steam branches.

Fig. 7 is a detail of a modified form of superheated steam header especially adapted 70 for use when the saturated steam is throttled, and having side outlets below the boiler shell for the superheated steam.

As here shown, the locomotive boiler comprises a shell 10 having the front tube sheet 12 through which the fire tubes 14 are received. The saturated steam header 16 of the superheater embodying this invention comprises a more or less fan shaped conduit having the front and rear walls 18 and 20 80 respectively which are inclined downwardly and forwardly away from the tube sheet and which terminate in a bottom wall 22 provided with a row of depending necks 24 which are adapted to be connected with the header branches. The header is provided with an enlarged neck 26 in the upper rear portion thereof which is adapted to be secured to the upper portion of the tube sheet around a saturated steam opening 28 therein. The superheated steam header 30 is of more or less 85 rectangular cross section and extends transversely of the boiler shell in the lower portion thereof and forward of the saturated steam header. Said superheated steam header is formed with a top wall 32 and a series of upstanding necks 34 which are spaced from each other along the length of the top wall and are adapted for connection with the branches of the superheated steam header.

90 95 100

The bottom wall 36 of said header extends through an opening in the lower portion of the boiler shell and has a flanged opening in the middle thereof to which the locomotive 5 throttle valve 38 may be connected if the locomotive is of the type wherein the throttle is installed in the superheated steam line. If the locomotive to which this invention is applied is of the type wherein the saturated 10 steam is throttled before it passes into the superheater, the saturated steam header may be closed at its bottom wall and may be provided, as shown in Fig. 7, with flanged extensions 40 at its opposite ends and on opposite 15 sides of the boiler shell for separate connection with pipes extended to the locomotive cylinders on opposite sides of the boiler.

The superheater units in each half of the boiler are identical. Each comprises a pair 20 of tubes 42 which are disposed in loops in the locomotive tubes 14 and are so arranged that each pair of tubes extends into and out of two adjacent locomotive tubes as is shown in the right hand side of Fig. 2. The similar 25 ends of the two tubes are integrally united with a tube 44 while the other similar ends of the tubes are similarly united with a tube 46. Said tubes 44 and 46 are disposed in different horizontal and vertical planes, or the tube 46 is disposed at one side of and above the tube 44. Said tube 44 is connected with the lower end of a short vertical tube 48 which tube forms a section of a branch of the saturated steam header. Said tube 46 is connected with the middle or upper portion of a similar but larger tube 50 which forms a branch for the superheated steam header. Said tubes 48 and 50 are of approximately the same height and have their upper and lower ends terminated in approximately the same horizontal plane and in line with the top and bottom of the unit. The pipes 48 and 50 of superposed superheater units are arranged one immediately above the other 45 as illustrated in Fig. 1 and are connected detachably together in a steam tight manner with each other and with their respective superheater headers by breakable male and female connections. For this purpose, the 50 lower ends of said pipes 48 and 50 are provided with cup shaped seats 52 in their lower ends. The upper ends of said pipes 48 and 50 are provided with conical seats 54 which fit into the cup shaped recesses 52 to form 55 steam tight joints between the two sections. The adjacent joints in the saturated and superheated steam branches are detachably clamped securely together by means of the upper and lower clamping bars 56, the opposite ends of each are provided with notches 58 in which the pipes 48 and 50 are received. The ends of said pipes are provided with flanges 60 against which said clamping bars 56 are adapted to be forced by clamping bolts 65 62. One set of clamping bolts serves to con-

nect the joints of two branch sections. The conical seats 54 of the uppermost saturated steam branch sections are received within the cup shaped ends 64 of the necks 24 of the saturated steam header and are secured detachably in a fluid tight manner by means including a suitable clamping plate 66. The lower ends of the lowermost superheated steam branch sections are similarly received and secured detachably in the necks 34 of the superheated steam header 30. The open upper ends of the superheated steam branches and the lower open ends of the saturated steam branches are closed by suitable removable sealing means 68. As thus arranged, the superimposed branch section 48 cooperate to form branches of the saturated steam header; and the branches depend vertically downwardly in front of the tube sheet. The superimposed branch sections 50 cooperate to form branches of the superheated steam header; and said branches extend vertically upward in front of the tube sheet and the saturated steam branches. The saturated and superheated steam branches are disposed in different vertical planes or are staggered relative to each other as is most clearly shown in Fig. 6 and the spacing between the branches is adapted to be greater than the horizontal dimensions of the superheater tubes so that the tubes can be withdrawn from the boiler tubes without disturbing any of the adjacent superheated tubes and branches.

The superheated and saturated steam branches are rigidly supported only at their ends, so that the tubes can expand freely, and deflect, under temperature changes.

When a defective superheater unit is to be withdrawn, the clamps connecting the sections 48 and 50 with contiguous upper and lower sections are removed and the sections are sprung out of their engagement with the contiguous sections, the springing being permitted due to the resiliency of the superheater tubes. A defective unit can then be withdrawn through the front of the locomotive boiler and replaced by an identical sound section. The branch sections 48 and 50 are adapted to be approximately as high as the tubes associated with those sections so that the tubes can be withdrawn freely through the space provided by the detached sections.

As here arranged all the superheater units in the right hand side of the boiler are identical while all the superheater units for the left hand side of the boiler are identical, although the superheater units for the two sides of the boiler are slightly different. With this arrangement only two types of superheater units need be kept in stock to replace any defective unit in the boiler, thus materially reducing the investment required to maintain a stock of superheater units for repair purposes.

The structure may be otherwise modified

without departing from the spirit of the invention.

We claim:

1. In a superheater for locomotive boilers, independent superheated and saturated steam headers having approximately parallel sectional branches extended therefrom which are free from rigid interconnections and are free to flex, means detachably connecting the sections, and looped superheated tubes having free and independent ends which are free to expand and flex independently of each other connected with said branch sections.

2. In a superheater for locomotive boilers, saturated and superheated steam headers each having sectional branches which are structurally independent, whereby they can flex independently of each other, means detachably connecting the branch sections, and superheater tubes connected with corresponding sections of both branches.

3. In a superheater for locomotive boilers, saturated and superheated steam headers having interspaced branches composed of a plurality of intercommunicating sections detachably connected in series, the sections of one branch being structurally independent of the sections of another branch, and superheater tubes connected with the sections of both branches.

4. In a superheater for locomotive boilers, an upper saturated steam header having spaced depending branches, a lower superheated steam header having spaced upstanding branches arranged in front of and in staggered parallel relation with the aforesaid branches, said branches composed of intercommunicating sections having means detachably connecting them in series, and looped superheater tubes having free ends connected with sections of both sets of branches, the branches being structurally free and independent and being free for relative displacement due to differences in expansion, the sections directly connected with said tubes having their ends terminated about in line with the tops and bottoms of said tubes.

5. In a superheater for locomotive boilers, an upper saturated steam header having spaced depending branches, a lower superheated steam header having upstanding branches arranged in front of and in parallel relation with said depending branches, the branches being structurally independent, said branches composed of intercommunicating sections arranged in series, and having inter-fitting male and female end-connections, means detachably connecting contiguous sections, and superheater tubes connected with said sections.

6. In a superheater for locomotive boilers the combination of a steam header, a plurality of super heater tubes each having an end

provided with a transverse section which is open at its opposite ends and is provided with ball and socket seats at its opposite open ends said sections being arranged in line with interfitting ball and socket seats and connected with said header and constituting a branch thereof, said interfitting ball and socket seats providing flexible connecting means for the sections by which the branch can flex along its length.

7. A superheater tube for locomotive boilers having its ends provided with transverse sections each having a passage therethrough which is open at both ends of the section and is in communication with the interior of the tube, said sections having attaching means at both ends thereof and being disposed adjacent and one in front of the other and being free and independent of each other.

8. A superheater tube for locomotive boilers having a closely looped section and having its ends provided with transverse sections each having a passage therethrough which is in communication with the interior of the tube, one section being disposed in front and at one side of the other section and both sections being free and independent of each other and terminated approximately at the top and bottom lines of the looped section of the tube.

9. In a superheater for locomotive boilers, the combination of saturated and superheated steam headers, superheater tubes having free and independent terminals providing header-branches, and means to connect said branches in intercommunicating series relation with each other and with said headers.

10. In a superheater for locomotive boilers, the combination with a boiler, its shell, and front tube sheet, of a saturated steam header disposed at the top of and in front of the tube sheet, a superheated steam header extended through an aperture in and located transversely of and in the boiler shell at the bottom thereof and in front of the tube sheet and having its bottom portion exposed below said boiler shell, branches connected with said headers and arranged in spaced parallel relation in front of the tube sheet, and superheater tubes connected with said branches.

11. In a superheater for locomotive boilers, the combination with a boiler, its shell, and front tube sheet, of a saturated steam header disposed at the top of and in front of the tube sheet, a superheated steam header extended through an aperture in and located transversely of and in the boiler shell at the bottom thereof and in front of the tube sheet and having its bottom portion exposed below said boiler shell, branches having connections with said headers and arranged in spaced parallel relation in front of the tube sheet, and superheater tubes connected with said branches and a throttle valve.

connected with said exposed portion of said superheated steam header below said boiler shell.

12. In a superheater for locomotive boilers, the combination with a boiler, its shell, and front tube sheet, of a saturated steam header disposed at the top of and in front of the tube sheet, a superheated steam header extended through an aperture in and located 10 transversely of and in the boiler shell at the bottom thereof and in front of the tube sheet, branches having detachable connections with said headers and arranged in spaced parallel relation in front of the tube sheet, said branches having intercommunicating sections arranged in series, means detachably connecting said sections in the aforesaid relation, and superheater tubes connected with the branch sections, and a steam outlet pipe connected with that portion only of said superheated steam header that is external 20 of said shell.

13. In a locomotive superheater, the combination of an upper saturated steam header, a lower superheated steam header, alternately-arranged depending and upstanding branches connected respectively with said headers, said branches characterized by being composed of a plurality of sections which are arranged in intercommunicating series relation and have means detachably connecting them together in such relation, and superheater tubes each having its ends connected one with a section of a depending branch and the other with a corresponding section of an upstanding branch, the sections of the depending and upstanding branches being free and separate, whereby the branches can be relatively displaced on expansion, the connections between said sections being breakable to admit of the removal in a lateral direction of said sections and the space between said branches vacated by the removed sections having such dimensions as to admit of the 40 withdrawal therethrough of the superheater tube connected with said removed sections without disturbing the relation of the other sections.

14. In a superheater for locomotive boilers, the combination with the boiler, its shell, and front tube sheet, of a saturated steam header disposed at the top of and in front of the tube sheet, and a superheated steam header mechanically separate from said saturated steam header disposed at the bottom of and in front of the tube sheet and extended through an aperture in and externally of the boiler shell at the bottom thereof, said superheated steam header having secured to its 50 external part thereof a superheated steam throttle valve which is located externally of and below the bottom of the boiler shell.

15. In a superheater for locomotive boilers, the combination with the boiler shell, of saturated and superheated steam headers lo-

cated mainly within said shell, and superheater tubes connected with said headers, said superheated steam header lying both within and without said boiler shell and having a superheated steam throttle valve which is located externally of and below said shell and is carried by said external part of said superheated steam header. 70

16. In a superheater for locomotive boilers, the combination of saturated and superheated steam headers which are supported independently of each other, and a superheated steam throttle valve directly connected mechanically with the superheated steam header only and being free from direct mechanical connection with said saturated steam header. 75

17. In a superheater for locomotive boilers, the combination with the boiler shell, of a saturated steam header, and a superheated steam header independent of said saturated steam header and extended through the boiler shell and having means for connection with the superheated steam piping of the boiler externally only of the shell. 85

18. In a superheater for locomotive boilers, the combination with the tube sheet of the boiler, of a fixed saturated steam header located at the top of the tube sheet, a fixed superheated steam header located at the bottom of the tube sheet, and a superheater tube consisting of a pipe extended in looped formation between said headers, the pipe including the ends thereof being free from restrictive inter-connections between its sections, and the ends having branches which are perpendicular to the body of the tube and are also free from restrictive inter-connections and have connections respectively with said headers, the arrangement being such that all portions of the superheater tube and its branches are free to expand in accordance with the temperature thereof. 95

In testimony whereof, we have signed our names to this specification.
